UNITED STATES PATENT OFFICE.

HECTOR VIVIAN LOUGH, OF PLAINFIELD, NEW JERSEY.

INTERNAL-COMBUSTION ENGINE.

1,211,950.

Specification of Letters Patent.

Patented Jan. 9, 1917.

Application filed July 30, 1912. Serial No. 712,247.

To all whom it may concern:

Be it known that I, HECTOR VIVIAN LOUGH, a subject of the King of Great Britain and Ireland, and residing at 159 East 5 Front street, Plainfield, Union county, State of New Jersey, United States of America, have invented a certain new and useful Internal-Combustion Engine, of which the following is a specification.

10 My invention relates to internal combustion engines, and my object is to produce an efficient construction having various advantages and points of novelty, as will be hereinafter set forth.

15 According to my invention the explosive charge is compressed into a separate combustion chamber which is arranged in a movable valve or member provided with ports. This is then, in the cycle of operations, moved out of communication with the compressor, or conduit from which the compressed charge enters the chamber, and the charge is ignited in the combustion chamber while the latter is closed and out of communication with both the power cylinder and the compressor. After a suitable interval for propagating the flame in the charge, the movable combustion chamber establishes communication with a power cylinder, the 20 charge being expanded behind the piston in the power cylinder. Also, preferably, the combustion chamber is scavenged after the power stroke by a charge of air. Preferably also, a plurality of pressure cylinders 25 are provided with alined compression cylinders, and the movable valve is rotated, with a plurality of ported combustion chambers therein, to receive the charges from the compressors and to deliver the same, after ignition, to the power cylinders in proper order.

30 In an engine constructed according to the invention combustion takes place in a closed and non-expanding chamber so that no back pressure can be produced while the gas remains in the combustion chamber for a sufficient portion of the crank cycle to completely propagate the flame through the mixture so that high speeds can be obtained with efficiency.

35 Further, according to the invention the compression chamber is separate from the expansion chamber so that the relative volume of the two chambers may be proportioned to expand to a much larger volume and lower terminal pressure on the working

stroke so that the thermal efficiency of the engine is increased.

Further, in an engine constructed according to the invention puppet valves and external moving parts are dispensed with, and 60 the exhaust takes place at low pressure, so that the engine is practically noiseless.

Referring to the accompanying drawings, which illustrate an example of a two-cylinder engine constructed according to the invention, Figure 1 is a sectional elevation of the engine; Fig. 2 is a sectional elevation at right angles to Fig. 1; Fig. 3 is a plan; Fig. 4 is a sectional plan taken on the line F—F Fig. 2; Fig. 5 is a horizontal section on the 70 line A—A Fig. 2; Fig. 6 is a similar section on the line B—B Fig. 2, Fig. 7 a horizontal section on the line C—C Fig. 2, Fig. 8 a similar view on the line D—D Fig. 2; Fig. 9 is a section through the valve of the engine on the line E—E Fig. 5; Fig. 10 is an enlarged section showing a part of the ignition device; Fig. 11 is an enlarged plan showing a portion of the ignition device; Fig. 12 is a sectional elevation on the line 80 G—G Fig. 11, while Fig. 13 is an enlarged view of a portion of the rack shown in Fig. 11.

75 In the engine illustrated the cylinders are constructed of two diameters, the portions *a a* forming the power cylinders and the portions *b b* of larger diameter acting as compressors. The piston is also formed of two diameters *c d* so that when it is at the bottom of its stroke an annular space is 80 formed in the portion of the cylinder *b*, and this space serves as a compression space. Between the cylinders there is situated a conical rotating valve *e* in which three combustion chambers 1, 2 and 3 are formed. 85 These combustion chambers are provided with ports arranged in three tiers. The top ports *f* register with the top or expansion chamber *a* of each cylinder. The second row of ports *g* registers with air ducts *h h* 90 communicating with respective air-tight crank chambers *l m*. The bottom row of ports *n* registers with ports in the annular chambers of the compressors *b b*. In the bottom of the valve are three by-passes *o* 95 which are always in communication with the carburetor which is attached at *p*, Fig. 2, and these by-passes have ports which register with the compressor ports and serve to supply the fresh gas to the same on the 100 105 110

downstroke of the piston. At the same level as the expansion chamber transfer ports f there are provided a set of three exhaust by-passes g carrying the exhaust gases from the cylinders to the exhaust chamber 22 and exhaust pipe 23 by the passages r in the waist of the valve. In line with the second row of ports g there are provided three ducts s communicating with a central duct 10 or well t open at the top to atmosphere, and these, by registering with the air ducts h k , supply air to the crank cases on the upstroke of the pistons. Three igniters u' u^2 u^3 are provided, one for each combustion chamber. Each of these comprises a spark plug u whose terminals are directly connected to the secondary of an induction coil contained in the igniter. Insulated primary wires lead from one terminal of the induction coil in each igniter to two diametrically opposite brushes b_1 b_4 b_2 b_5 b_3 b_6 situated on the rotating valve. One of these commutator brushes is shown on an enlarged scale at Fig. 10. The current is led from the battery or low-tension magneto to the insulated terminal x , from which it passes by a spring-piece w to the contact roller z . This roller is built up of an insulated outer shell 4 of metal supported on rubber 5 with a central wearing bushing 6, the object of interposing the rubber being to get a firm but yielding contact, at the same time noiseless and non-conducting. The roller is mounted on an eccentric pin 7 adjustably held in the member 8 as shown in Fig. 3, and may be adjusted by turning the pin 7. The roller is carried on a geared segment 8 sliding on a dovetail piece 20 which forms part of the cylinder casting and is actuated 35 by a pinion 9 on a shaft 10. The second terminal of the battery or low-tension magneto is connected to a suitable point on the engine, as is also the second terminal of the primary coil of each igniter by the wires c_1 c_2 c_3 connecting to the valve body 21. As each igniter is connected to two commutator contacts it will be seen that each combustion chamber will receive a spark twice during each revolution of the valve, so that six explosions take place during one turn of the valve.

The operation of the engine is as follows:—During each down-stroke of the piston the compressor b draws a charge of gas 55 from the carburetor through one of the inlet by-passes o at the bottom of the valve. The up-stroke of the piston compresses the charge in the annular space in the cylinder b and forces it into one of the combustion chambers in the valve through the lowest port n . The rotating valve then cuts off communication with the compressor b and holds the compressed charge cut off from communication with any other chamber. 60 The compressed charge is now ignited in the combustion chamber, and a whole downstroke of the piston may, if required for instance at high speeds, be devoted to the spreading of the flame through the mass. During this downstroke of the piston first 70 considered, the other piston has ascended and drawn into its crank chamber m through the air duct k and corresponding air port s in the valve a fresh charge of air. The top port f of the combustion chamber 75 is now about to register with the top port of the second cylinder a , the piston of which is at the top. The expanding gases from the combustion chamber therefore force the second piston down. Near the bottom of 80 the stroke the top combustion chamber port in the valve registers with one of the two exhaust passages 24, 25 in the waist of the valve, and at the same instant, or shortly after, the middle port g of the combustion 85 chamber coincides with the air duct k of the crank case m , where the air is now compressed owing to the descent of the piston. This air now rushes into the combustion chamber in the valve and drives out the 90 burnt gases through the exhaust passage, at the same time cooling the valve. The exhaust by-pass in the top of the valve is also now in communication with the port of the second cylinder a and has thus relieved the 95 expansion chamber of its pressure. During the return stroke of the second piston the exhaust by-pass remains open so that the piston clears out the burnt gas from the expansion chamber. The exhaust by-pass is 100 closed, however, a little before the end of the stroke so as to imprison a small amount of gas which is compressed to approximately the expansion pressure again and fills the clearance at the end of the cylinder. 105 This results in a saving of the amount of subsequent charge necessary to fill the clearance space and also has a cushioning effect on the piston. The valve is driven at one-third the speed of the crank shaft by means 110 of a spiral gear 11 on this shaft which engages with a second spiral gear 12 fixed to a shaft 18 carried by a bracket 19 secured to the crank shaft casing. A spur gear 13 is secured to the other end of the shaft 18 and meshes 115 with a second spur gear 14 supported in a bearing 26 formed on the cylinder casting. The connection from the gear 14 to the valve is made through a more or less flexible spindle 15, which is rotatably connected at 120 one end to the gear by means of a key or projection 27 on the latter engaging in key-way or groove 28 in the spindle. The other end of the spindle is connected at 29 to the lower end of the valve. The spindle 15 is 125 slidable longitudinally of the spur gear 14 and is adjustable in this direction by means of a split nut 16 engaging a flange 17 on the spindle, said nut being threaded on to the end of the hub 30 of the gear 14. The ob- 130

ject of this adjustment is to take up any wear of the tapered valve and the flange 17 is free to move sidewise in the nut 16 so that absolute concentricity need not be maintained between the valve and its driving gear.

Having now described my invention what I claim as new and desire to secure by Letters Patent is:—

- 10 1. In an internal combustion engine, the combination of a power cylinder, a movable valve having a ported combustion chamber therein, a frame in which said valve moves, having a conduit for a compressed charge, and a passage leading to said power cylinder, and means for moving said valve to successively establish communication between said conduit and said chamber to permit a compressed charge to enter said chamber; to cut off such communication; and to establish communication between said chamber and power cylinder, the ports of said chamber being out of communication with said passage for a period after communication with said conduit has been cut off; and means for igniting the charge in said chamber after communication has been cut off from said conduit and before communication has been established through said passage with said power cylinder.
- 15 2. In an internal combustion engine, the combination of a plurality of power cylinders, a movable casing divided into a plurality of combustion chambers, having ports, a frame in which said casing moves, having passages leading to said power cylinders, means for compressing charges into said chambers, when the latter are in proper position, means for moving said casing in a cycle of operations to cause the charges to be compressed into said chambers; to cut each casing off from communication with said first-mentioned means; and to place each chamber in communication with a power cylinder through one of said passages; and means for igniting the charge in each chamber after communication has been cut off from said first-mentioned means and before communication has been established through one of said passages with a power cylinder.
- 20 3. An internal combustion engine, comprising in combination, a power cylinder, a combustion chamber distinct from said cylinder, a compression cylinder coöperating with said power cylinder, means for introducing a charge into said compression cylinder, means for establishing communication between said compression cylinder and said combustion chamber, to allow compression of the charge into said chamber, and for cutting off said communication, a second power cylinder, means for establishing communication between said combustion chamber and said second power cylinder, to

allow expansion of the ignited gases in said cylinder, and means for subsequently establishing communication between said combustion chamber and the other side of the piston in said compression cylinder, in order to introduce a charge of scavenging air into said chamber.

4. An internal combustion engine, comprising in combination, a power cylinder, a combustion chamber distinct from said cylinder, a compression cylinder coöperating with said power cylinder, means for introducing a charge into said compression cylinder, means for establishing communication between said compression cylinder and said combustion chamber, to allow compression of the charge into said chamber, and for cutting off said communication, a second power cylinder, means for establishing communication between said combustion chamber and said second power cylinder, to allow expansion of the ignited gases in said cylinder, and means for subsequently introducing a charge of scavenging air into said combustion chamber.

5. An internal combustion engine comprising in combination a pair of power cylinders, a plurality of combustion chambers distinct from said cylinders, a compression cylinder coöperating with each of said power cylinders, means for introducing charges into said compression cylinders in proper sequence, means for establishing communication between each of said compression cylinders and said combustion chambers in succession, to allow compression of said charges into said chambers, and for cutting off said communication, and means for establishing communication between each of said power cylinders and said combustion chambers in succession, to allow of the expansion in one power cylinder of the gases compressed by the compression cylinder of the other power cylinder.

6. An internal combustion engine comprising in combination, a pair of power cylinders, a plurality of combustion chambers distinct from said cylinders, a compression cylinder coöperating with each of said power cylinders, means for introducing charges into said compression cylinders in proper sequence, means for establishing communication between each of said compression cylinders and said combustion chambers in succession, to allow compression of said charges into said chambers, and for cutting off said communication, means for establishing communication between each of said power cylinders and said combustion chambers in succession, to allow of the expansion in one power cylinder of the gases compressed by the compression cylinder of the other power cylinder, and means for subsequently establishing communication between said combustion chambers, in succession, and

the other side of the piston in each of said compression cylinders in order to introduce charges of scavenging air into said chambers.

5 7. An internal combustion engine comprising in combination, a pair of power cylinders, a plurality of combustion chambers distinct from said cylinders, a compression cylinder coöperating with each of said power cylinders, means for introducing charges into said compression cylinders in proper sequence, means for establishing communication between each of said compression cylinders and said combustion chambers in succession, to allow compression of said charges into said chambers, and for cutting off said communication, means for establishing communication between each of said power cylinders and said combustion 20 chambers in succession, to allow of the expansion in one power cylinder of the gases compressed by the compression cylinder of the other power cylinder, and means for subsequently introducing a charge of scavenging air into each of said combustion chambers.

8. An internal combustion engine, comprising in combination, a plurality of power cylinders, a plurality of combustion chambers distinct from said cylinders, a compression cylinder coöperating with each of said power cylinders, means for introducing charges into said compression cylinders in proper sequence, means for establishing communication between each of said compression cylinders and said combustion chambers in succession, to allow compression of said charges into said chambers, and for cutting off said communication, and 30 means for establishing communication between each of said power cylinders and said combustion chambers in succession, to allow of the expansion in one power cylinder of the gases compressed by the compression cylinder of another power cylinder.

9. An internal combustion engine, comprising in combination, a plurality of power cylinders, a plurality of combustion chambers distinct from said cylinder, a compression cylinder coöperating with each of said power cylinders, means for introducing charges into said compression cylinders in proper sequence, means for establishing communication between each of said compression cylinders and said combustion chambers in succession, and to allow compression of said charges into said chambers, for cutting off said communication, means for establishing communication between each of said power cylinders and said combustion chambers in succession, to allow of the expansion in one power cylinder of the gases compressed by the compression cylinder of another power cylinder, and

means for subsequently establishing communication between said combustion chambers, in succession, and the other side of the piston in each of said compression cylinders in order to introduce charges of scavenging air into said chambers.

10. An internal combustion engine comprising in combination, a plurality of power cylinders, a plurality of combustion chambers distinct from said cylinders, a compression cylinder coöperating with each of said power cylinders, means for introducing charges into said compression cylinders in proper sequence, means for establishing communication between each of said compression cylinders and said combustion chambers in succession, to allow compression of said charges into said chambers, and for cutting off said communication, means for establishing communication between each of said power cylinders and said combustion chambers in succession, to allow of the expansion in one power cylinder of the gases compressed by the compression cylinder of another power cylinder, and means for subsequently introducing a charge of scavenging air into each of said combustion chambers.

11. An internal combustion engine, comprising in combination a pair of power cylinders, a movable casing divided into a plurality of combustion chambers, a compression cylinder coöperating with each of said power cylinders, means for introducing charges into said compression cylinders in proper sequence, and means for moving said casing to establish communication between each of said compression cylinders and said combustion chambers in succession, in order to allow compression of said charges into said chambers; to cut off said communication; and to establish communication between each of said power cylinders and said combustion chambers in succession, to allow of the expansion in one power cylinder of the gases compressed by the compression cylinder of the other power cylinder.

12. An internal combustion engine, comprising in combination a pair of power cylinders, a rotatable casing divided into a plurality of combustion chambers, a compression cylinder coöperating with each of said power cylinders, means for introducing charges into said compression cylinders in proper sequence, and means for rotating said casing to establish communication between each of said compression cylinders and said combustion chambers in succession, in order to allow compression of said charges into said chambers; to cut off said communication; and to establish communication between each of said power cylinders and said combustion chambers in succession, to allow

of the expansion in one power cylinder of the gases compressed by the compression cylinder of the other power cylinder.

13. An internal combustion engine, comprising in combination a plurality of power cylinders, a movable casing divided into a plurality of combustion chambers, a compression cylinder coöperating with each of said power cylinders, means for introducing charges into said compression cylinders in proper sequence, and means for moving said casing to establish communication between each of said compression cylinders and said combustion chambers in succession, in order to allow compression of said charges into said chamber; to cut off said communication; and to establish communication between each of said power cylinders and said combustion chambers in succession, to allow of the expansion in one power cylinder of the gases compressed by the compression cylinder of another power cylinder.

14. An internal combustion engine, comprising in combination a plurality of power cylinders, a rotatable casing divided into a plurality of combustion chambers, a compression cylinder coöperating with each of said power cylinders, means for introducing charges into said compression cylinders in proper sequence, and means for rotating said casing to establish communication between each of said compression cylinders and said combustion chambers in succession, in order to allow compression of said charges into said chamber; to cut off said communication; and to establish communication between each of said power cylinders and said combustion chambers in succession, to allow of the expansion in one power cylinder of the gases compressed by the compression cylinder of another power cylinder.

15. An internal combustion engine, comprising in combination, a power cylinder, a combustion chamber distinct from said cylinder and adapted to receive a charge, a compression cylinder coöperating with said power cylinder, means for establishing communication between said combustion chamber and said power cylinder to allow of the

expansion of the ignited charge in the cylinder, and means for establishing communication between said chamber and one side of the piston in the compression cylinder, to force a charge of scavenging air into said chamber.

55

16. An internal combustion engine, comprising in combination, a power cylinder, a combustion chamber distinct from said cylinder, a compression cylinder coöperating with said power cylinder, means for introducing a charge into said compression cylinder, means for establishing communication between said compression cylinder and said chamber, to compress a charge into the latter, and for cutting off said communication, means for establishing communication between said combustion chamber and said power cylinder to allow of the expansion of the ignited charge in the cylinder, and means for establishing communication between said chamber and the other side of the piston in the compression cylinder, to force a charge of scavenging air into said chamber.

60

65

70

75

17. An internal combustion engine, comprising in combination a power cylinder, a movable casing having a combustion chamber therein adapted to receive a charge, a compression cylinder coöperating with said power cylinder, a passage formed in the engine casing and communicating with said compression cylinder, a port in said movable casing leading into said combustion chamber, and means for moving said casing to establish communication between said combustion chamber and said power cylinder to allow expansion of the ignited charge in the cylinder, and for subsequently bringing said port into register with said passage to allow the introduction of a charge of scavenging air from said compression cylinder into said chamber.
